US0D1013344S

(12) **United States Design Patent** (10) **Patent No.:** **US D1,013,344 S**
(45) **Date of Patent:** **** Feb. 6, 2024**

(54) **SHOE SOLE**

(71) Applicant: **Skechers U.S.A., Inc. II**, Manhattan Beach, CA (US)

(72) Inventor: **James Frantz**, Torrance, CA (US)

(73) Assignee: **Skechers U.S.A., Inc. II**, Manhattan Beach, CA (US)

(**) Term: **15 Years**

(21) Appl. No.: **29/895,139**

(22) Filed: **Jun. 16, 2023**

Related U.S. Application Data

(62) Division of application No. 29/831,142, filed on Mar. 17, 2022, now abandoned.

(51) **LOC (14) Cl.** **02-04**

(52) **U.S. Cl.**

USPC **D2/947**; D2/959

CLAIM

The ornamental design for a shoe sole, as shown and described.

DESCRIPTION

FIG. 1 is a side elevation view of a first embodiment of the shoe sole; and,

FIG. 2 is a side elevation view of a second embodiment of the shoe sole.

The broken lines shown in the drawings represent environmental structure in the form of a shoe upper as well as portions of the shoe sole that form no part of the claimed design.

1 Claim, 2 Drawing Sheets
